VALVE MECHANISM FOR GAS ENGINES

James O. Hosmon and Edward W. Anderson,
San Diego, Calif.Application November 22, 1932
Serial No. 643,856

5 Claims. (Cl. 123—188)

Our invention relates to valve mechanisms for gas engines, and the objects of our invention are:

First, to provide for preventing the collection of carbon or other deleterious matter around the valve stem, particularly the exhaust valve stem of an internal combustion engine, thereby preventing sticking of the valve due to the accumulated carbon binding in the valve stem guide;

Second, to provide a mechanism of this class which may be readily and quickly installed in a conventional internal combustion engine;

Third, to provide a mechanism of this class which in no wise interferes with the normal operation of the valves;

Fourth, to provide a mechanism of this class which is particularly simple and economical of manufacture;

Fifth, to provide a mechanism of this class which not only prevents the accumulation of carbon on the valve stem but also tends to maintain the stem in a lubricated condition particularly at its juncture with the guide;

Sixth, to provide a mechanism of this class which prevents undue heating of the valve stem particularly at the juncture with its guide; and

Seventh, to provide on the whole a novelly constructed valve stem cleaner for internal combustion engines which is simple and economical of manufacture, durable, efficient in its action and which will not readily deteriorate or get out of order.

With these and other objects in view as will appear hereinafter, our invention consists of certain novel features of construction, combination and arrangement of parts and portions as will be hereinafter described in detail and particularly set forth in the appended claims, reference being had to the accompanying drawing and to the characters of reference thereon which form a part of this application, in which:

Figure 1 is an outline view of a conventional exhaust valve and its stem with adjacent portions of a cylinder block shown fragmentarily and in section, and illustrating our mechanism in position by means of a longitudinal sectional view thereof; Fig. 2 is a partial plan partial elevational view of our mechanism taken substantially along the line 2—2 of Fig. 1; and Fig. 3 is a side elevational view of the shell member forming a part of our mechanism.

Similar characters of reference refer to similar parts and portions throughout the several views of the drawing.

The conventional exhaust valve, designated A in Fig. 1, comprises a head A1 which seats over

the end of an exhaust port B1 formed in the cylinder block B. The exhaust port B1 curves to one side and its bottom portion is provided with a valve guide C in alignment with the exhaust valve A which protrudes upwardly into the exhaust valve port. The guide C receives the valve stem, designated A2, of the valve.

Our mechanism includes a shell member 1 having a cylindrical portion 1a adapted to fit over the protruding portion of the valve guide C. 65 This portion of the valve guide C may be machined if necessary so that the shell 1 may be pressed tightly thereon. The upper portion of the shell protrudes above the guide C and terminates in an inturned flange 1b leaving an opening 1c which loosely receives the valve stem A2. The extended portion of the shell 1 forms with the ends of the valve guide C a small chamber 1d in which is positioned a collar member 2. The collar member 2 is provided with a bore there- 75 through which snugly but slidably receives the stem A2 of the valve; said collar fits loosely within the chamber 1d.

Operation of our mechanism is as follows: Reciprocation of the valve and its stem causes the 80 collar 2 to vibrate or reciprocate to a certain extent therewith. Oil which works up the guide is delivered to the collar and is wiped thereby on the valve stem just above the guide but within the shell 1 so that the entire length of the valve 85 stem within the guide maintains a lubricated condition. However, excess carbon which may collect on the protruding portion of the valve stem is continually worn off by the action of the collar. Furthermore, the shell 1 seals the portion of the stem entering the guide from direct 90 contact with the hot exhaust gases.

Though we have shown and described a particular construction, combination and arrangement of parts and portions, we do not wish to 95 be limited to this particular construction, combination and arrangement, but desire to include in the scope of our invention the construction, combination and arrangement substantially as set forth in the appended claims.

Having thus described our invention, what we claim as new and desire to secure by Letters Patent is:

1. In a mechanism of the class described, the combination with a valve stem and its guide, of 100 a collar slidably mounted on said valve stem above said guide, and a retainer for said collar supported from said guide.

2. In an internal combustion engine having 110 valves in which the stems thereof extend across

or through passages controlled by said valves and into guides intersecting said passages, the combination with a valve, its stem and guide, of a collar slidably mounted on said valve stem between the valve and guide, and a retainer for said collar supported from said guide.

3. In a mechanism of the class described, the combination with a valve stem and its guide, of a collar slidably mounted on said valve stem above said guide, a shell continuing upwardly from said guide and surrounding said collar and stem, and an inturned flange at the extremity of said shell for restraining said collar.

4. In an internal combustion engine having valves in which the stems thereof extend across or through passages controlled by said valves and into guides intersecting said passages, the

combination with a valve, its stem and guide, of a collar slidably mounted on said valve stem between the valve and guide, a shell continuing upwardly from said guide and surrounding said collar and stem, and an inturned flange at the 80 extremity of said shell for restraining said collar.

5. The combination with a valve, particularly the valve stem and its guide wherein the guide protrudes into the passage controlled by the head of said valve, of a cylindrical shell press fitted 85 upon and extending beyond the protruding end of said guide, an inturned flange at the extremity of said shell, and a collar slidably mounted on said valve stem within said shell between said flange and the extremity of said guide.
